UNITED STATES PATENT OFFICE.

JOSIAH H. EDWARDS, OF LOS ANGELES, CALIFORNIA.

SASH-FASTENER.

1,327,594.

Specification of Letters Patent.

Patented Jan. 6, 1920.

Application filed October 24, 1918. Serial No. 259,546.

To all whom it may concern:

Be it known that I, JOSIAH H. EDWARDS, a citizen of the United States, residing at Los Angeles, in the county of Los Angeles 5 and State of California, have invented new and useful Improvements in Sash-Fasteners, of which the following is a specification.

My invention relates to a window locking device and more particularly to a concealed 10 window locking device.

An object of my invention is to provide a concealed sash locking device for windows having concealed sash cords and pulleys.

Another object is to provide a concealed 15 sash locking device for windows of the above described type which will securely hold both upper and lower sashes in any desired position.

With these and other objects in view my 20 invention consists in the construction, combination and arrangement of parts herein-after described and claimed.

In the accompanying drawings which form a part of this specification,

25 Figure 1 is a view in perspective of a window, seen from the inside, with parts broken away to disclose the sash chain, the pulley and the locking parts of the sash locking device embodying the principles of 30 my invention.

Fig. 2 is a reduced view of the complete window shown in Fig. 1.

Fig. 3 is a horizontal sectional view taken on the line 3—3 of Fig. 1.

35 Fig. 4 is an enlarged fragmentary sectional view taken on the line 4—4 of Fig. 1.

As shown in Fig. 1, the window comprises an upper sash 10 and a lower sash 11 mounted between jambs 12 and 13 of a

40 window frame, finished with an inner casing 14. The jambs 12 and 13 have pulleys 15 and 16 fixed in slots 17 formed approximately midway between their upper and lower ends. Sash chains 18 and 19 having

45 weights 20 attached to their outer ends are roved over the pulleys 15 and 16 and have their inner ends made fast to the sashes 10 and 11. Sash chains 18 are attached to the lower end of the lower sash stiles 24', and

50 sash chains 19 are attached to the lower ends of the upper sash stiles 24, so that the weight of the lower sash is in its upper position and the weight of the upper sash is in its lower position when the sashes are

55 closed, as shown in Fig. 1. Grooves 21 are cut in the marginal edges of the upper and

lower sash stiles to provide clearance for the pulleys and chains. The stiles of the lower sash have lugs 22 extending above the top rail to provide for locking the lower sash 60 in its closed position.

Shallow holes 23 are bored into the sash stiles 24 and 24' on one side of the window, the boring being done from the outer edge of the sash toward the glass. These holes, 65 which are continued into the lug 22 of the lower sash, form sockets adapted to receive a locking bolt or shank. A metal crossbar or cross plate 25 is fixed on the back face of the window jamb 13 directly above the sash 70 pulleys 15 and 16 by screws driven into the jamb 13 through holes provided for them in the cross plate. Thumb-screws 27 and 28, having elongated shanks 29 adapted to register with the sockets 23, extend inwardly 75 through tapped holes in the cross plate 25 and holes 13' in the jamb 13, so as to be in vertical alignment with sockets 23. The purpose of the thumb-screws is to engage with the sockets 23 in the sash stiles, thus locking 80 the sashes in any desired position. Thumb-screw 27 is adapted to engage with the sockets in the lower sash, and thumb-screw 28 with the sockets in the upper sash. A hand hole 30 is cut in the casing on the side 85 of the window which is provided with the locking device, and a swinging door 31 is mounted in the opening being held therein by a pivot pin 32 driven from the edge of the casing through its upper end. The 90 swinging door is mounted flush with the casing and is adapted to swing into the weight well 33 when it is desired to get at the thumb-screws.

The operation is evident. The window- 95 sashes are moved upwardly or downwardly in the usual way, the thumb-screws being turned backwardly far enough to clear the sockets. When it is desired to lock the window-sash in any position the hand is pressed 100 against the lower end of the pivoted door 31, which readily yields, whereupon the hand is passed into the weight well and the thumb-screw is turned forwardly until its shank 29 enters one of the sockets 23, 105 thus locking the sash against any upward or downward movement.

While I have shown my sash locking device, as now known to me, it will be understood that various changes in construction, 110 combination and arrangement of parts may be made by those skilled in the art with-

out departing from the spirit of my invention as claimed.

I claim:

A sash fastener comprising a window casing having a well at the side of the window opening intermediate of the top and bottom and a jamb forming the inner side of the well, an upper and lower sash mounted to slide vertically within the window casing

10 against the jamb, said upper and lower

sashes having sockets formed in the marginal edges of adjacent stiles, a cross plate fixed to the back face of the jamb and having tapped holes, thumb-screws mounted in the holes and having elongated shanks to 15 engage in the sockets, and a door opening into said well to provide access to the screws.

In testimony whereof I have signed my name to this specification.

JOSIAH H. EDWARDS.
